UNITED STATES PATENT OFFICE.

CLAUDE W. MORRIS AND HAROLD R. MORRIS, OF CHICAGO, ILLINOIS.

ADJUSTABLE HOLDER FOR WRIST-WATCHES.

1,143,548.

Specification of Letters Patent. Patented June 15, 1915.

Application filed January 13, 1915. Serial No. 2,061.

To all whom it may concern:

Be it known that we, CLAUDE W. MORRIS and HAROLD R. MORRIS, citizens of the United States, residing at Chicago, in the 5 county of Cook and State of Illinois, have invented a certain new and useful Improvement in Adjustable Holders for Wrist-Watches, of which the following is a specification.

10 This invention relates to devices for applying a watch to a wrist bracelet so that it can be carried on the wearer's, usually a lady's, wrist.

15 The object of the invention is to provide a device of this kind for applying a metallic bracelet to a watch or vice versa in which the device for taking hold of the watch is adjustable to, within certain limits, fit watches of different sizes.

20 The invention consists in making a gripping device for holding the watch which, while so adjustable to size, is also very simple and neat in construction, easy to make and repair and not readily liable to get out 25 of order, more particularly one in which the adjustment is made in such a way that a substantially smooth surface is presented both to the back of the watch to be gripped and to the hand of the user wearing the 30 same, thus adding greatly to the practical utility of the device; this without sacrificing any strength of the gripping device.

The invention also consists in details of construction which will be hereafter more 35 fully set forth, in the specification and claims.

40 Referring to the drawings in which similar numerals refer to the same parts throughout the several views, Figure 1 is a plan view of mechanism illustrating this invention in its preferred form, the gripping device being adjusted for the smallest size of watch which the device is designed to accommodate, the watch itself being shown in dotted lines.

45 Fig. 2 is an inverted plan view of the parts appearing in Fig. 1, the watch being removed and a changed position of the parts being shown in dotted lines. Fig. 3 is a side view of the parts shown in Fig. 1, the bracelet 50 chain being removed. Fig. 4 is a transverse view taken on the line 4—4, Fig. 1.

In order to secure the watch 10 between the ends 12 and 14 of the bracelet chain 15 of ordinary construction, the gripping device 55 shown in the drawings and hereafter

fully described is provided. This gripping device comprises a base member made in two separable parts 16 and 16^a adjustable with reference to each other as hereafter described, one of said parts as 16 being 60 provided with a loop 18 adapted to receive the stem 20 of the watch, the other part as 16^a being provided with spring fingers or clips 21 spaced apart as shown in the drawings and adapted to embrace separated points 65 on opposite portions of the watch opposite to the loop 18 heretofore referred to, the result being that when the watch 10 is fitted into the device, as shown in the drawings, it is securely held in place. The part 16^a is provided with a ring or loop 22 engageable by the end 14 of the bracelet chain 15 as shown.

70 The construction just described provides a satisfactory method of applying a watch of given size to a bracelet and thence to the 75 hand or wrist of the wearer, when the plate 16, 16^a is made of one solid piece with smooth upper and lower surfaces engaging respectively the watch and the hand of the wearer, but as watches suitable for wearing 80 on the wrist vary considerably in size and it is both expensive and inconvenient for a jeweler to carry a stock of gripping devices to fit all watches, it is very important to provide a gripping device of this general 85 type which can be adjusted to take different sizes of watches. This result is accomplished in the following manner: The base plate is made in two parts 16, 16^a separated, generally speaking, along the transverse line 90 24 running preferably substantially parallel to the line of the spring clips 21 and intermediate between them and the loop 18. One of the parts as 16 is provided with a plurality of, preferably three or more, extending 95 fingers 26 and 27 staggered alternately on opposite surfaces of the plate 16 and fitting in correspondingly arranged recesses cut in the opposite member as 16^a, as clearly appears in the drawings. In the particular 100 case here illustrated there are two of these fingers 26 extending from the top surface of the member 16 and one finger 27 extending from the bottom surface of part 16. These 105 fingers 26 and 27 and the recesses in which they fit are so proportioned that, as is clearly shown in Fig. 4, the upper surface 28 is always substantially smooth in contact with the watch, while the lower surface 30 is also correspondingly substantially level and 110

smooth when applied to the hand of the user in all positions of these fingers 26 and 27 longitudinally in their respective slots. The parts are held in this relationship while 5 permitting adjustment by virtue of pin and slot connections in at least two of the fingers above referred to, the particular form here illustrated calling for slots 32 in the member 16^a, the pins 34 in the fingers 26 extending through said slots 32. Obviously 10 the relationship of these pins and slots may be reversed with reference to the other parts named without departing from this invention. Some sort of locking device has to be 15 provided, the particular embodiment here illustrated taking the form of a screw 36 passing through a hole in finger 27 and removably insertible in a selected one of the three holes 38, 39 and 40 in the member 16^a. 20 Watches designed to be used in connection with this device are ordinarily small ladies' watches and do not vary more than about an eighth of an inch or less between successive sizes, so that the spacing between these screw 25 holes 38-40 is correspondingly slight but nevertheless very important in insuring the proper fit of the gripping device to a particular watch to which it may be applied. The loop 18 is made of such a size and shape 30 that, while it admits the stem 20 of the watch stem through it, it nevertheless holds the watch and the plate 16 in proximity to each other under all circumstances.

Except as specifically noted, the exact 35 construction is not material, and may be varied within reasonable limits without departing from the invention.

Having thus described our invention, what we claim as new and desire to secure by Letters Patent, is:

1. In a device of the class described, two interfitting parts locatable along the back of a watch movable with reference to each other, to, in all positions, present substantially continuous smooth faces, one to the watch, the other to the hand of the user, means for detachably securing said parts in selected positions with reference to each other, and means carried by each of said 50 parts for retaining a watch in contact with them.

2. In a device of the class described, two interfitting parts locatable along the back of a watch movable in straight lines with 55 reference to each other to, in all positions, present substantially continuous smooth faces, one to the watch, the other to the hand of the user, means for detachably securing said parts in selected positions with reference to each other, and means carried by said parts for retaining a watch in contact with them.

3. A gripping device for a watch comprising a substantially parallel surfaced plate 65 provided with suitably spaced means ex-

tending from its edges for gripping a watch, and means for having a wrist bracelet or chain attached thereto, said plate being made in two separable parts adjustable lengthwise with reference to each other arranged to, in all positions, present substantially continuous smooth faces, one to the watch, the other to the hand of the user, and arranged to accommodate watches of different sizes between said gripping means in 75 combination with means for detachably securing the parts of the plate in selected adjusted positions corresponding to the sizes of the respective sizes of the watches to which the device is applied.

4. A gripping device for a watch comprising a substantially parallel surfaced plate carrying suitably spaced means on its edges for holding a watch and for having a wrist bracelet attached thereto, said plate being 80 divided in two parts, one of which carries a plurality of fingers extending along the other part and connected thereto by a pin and slot connection permitting longitudinal adjustment of the two parts with reference 85 to each other, and means for securing said parts of the plates in desired positions, the plate parts and connections being constructed and arranged to, in all positions, present substantially continuous smooth 90 faces, one to the watch, the other to the hand of the user.

5. A gripping device for a watch comprising a substantially parallel surfaced plate carrying suitably spaced means on its edges for holding a watch and for having a wrist bracelet attached thereto, said plate being divided in two separable parts, a plurality of fingers extending from one of said parts of the plate entering and traveling in recesses formed in the faces of the other part of the plate so as to permit movement of the parts of the plate with reference to each other without substantially destroying the parallelism of the faces of the plate, and means operating in connection with said fingers for detachably securing the parts of the plate in selected adjusted positions with reference to each other.

6. A gripping device for a watch comprising a substantially parallel surfaced plate carrying suitably spaced means on its edges for holding a watch and for having a wrist bracelet attached thereto, said plate being divided in two separable parts, a plurality of fingers extending from one of said parts of the plate entering and traveling in recesses formed in the faces of the other part of the plate so as to permit movement of the parts of the plate with reference to each other without substantially destroying the parallelism of the faces of the plate, alternate ones of said fingers being located upon opposite faces of the plate, and means operating in connection with said fingers for

detachably securing the parts of the plate in selected adjusted positions with reference to each other.

7. In a device of the class described, a two-part plate provided with watch retaining devices in which one of the parts of the plate contains projecting fingers alternately engaging opposite sides of the other part of the plate while permitting longitudinal movement in the direction of the lengths of said fingers of the parts of the plate with reference to each other, and means for detachably securing the parts together in selected positions with reference to each other.
- 10 8. In a device of the class described, a two-part plate provided with watch retaining devices in which one of the parts of the plate contains projecting fingers alternately engaging opposite sides of the other part of the plate while permitting longitudinal movement in the direction of the lengths of said fingers of the parts of the plate with reference to each other, said fingers lying in suitably formed recesses in the opposite part 20 of the plate so that the faces of the plate are substantially parallel in all positions of the parts, and means for detachably securing the parts together in selected positions with reference to each other.
- 25 9. In a device of the class described, a two-part plate provided with watch retaining devices in which one of the parts of the plate carries projecting fingers alternately lying in slots on opposite faces of the other part of the plate so that longitudinal movement of the parts of the plate with reference

to each other is permitted without destroying the substantially parallel character of the opposite faces of the plate, pin and slot connections between certain of said fingers 40 and the opposite part of the plate which they engage, and means for detachably securing the parts of the plate in adjusted position.

10. In a device of the class described, a gripping device comprising a plate made in two parts 16 and 16^a provided respectively with watch retaining devices, one of said parts of the plate as 16 being provided with a plurality of fingers 26 and 27 extending 50 from the edge of said member 16 which is adjacent to the part 16^a, the fingers 26 lying on one face of the plate, the finger 27 lying on the opposite face of the plate, both sets of fingers lying in recesses in the part 16^a 55 of the plate, pin and slot connections 32—34 between the fingers 26 and part 16^a of the plate, a detachable screw 36 insertible through a hole in the finger 27 on plate 16 and selectively placed holes in the part 16^a 60 of the plate for securing the parts in adjusted position, all of the parts being arranged and disposed substantially as shown and described for the purposes set forth.

In witness whereof we have hereunto subscribed our names in the presence of two witnesses.

CLAUDE W. MORRIS.
HAROLD R. MORRIS.
